UNITED STATES PATENT OFFICE

**OSCAR E. BROWN, OF MOUNT LEBANON, PENNSYLVANIA, ASSIGNOR TO UNITED STATES
GLASS COMPANY, OF PITTSBURGH, PENNSYLVANIA, A CORPORATION OF PENNSYLVANIA**

DESIGN FOR AN ASH TRAY

Application filed December 27, 1930. Serial No. 38,130. Term of patent 7 years.

To all whom it may concern:

Be it known that I, OSCAR E. BROWN, a citizen of the United States, residing at Mount Lebanon, in the county of Allegheny and State of Pennsylvania, have invented a new, original, and ornamental Design for an Ash Tray, of which the following is a specification, reference being had to the accompanying drawing, forming part thereof.

The figure is a perspective view of an ash tray showing my new design.

I claim:

The ornamental design for an ash tray or similar article substantially as shown.

OSCAR E. BROWN.
